UNITED STATES PATENT OFFICE.

HENRY H. HANSEN, OF LA GRANGE, ILLINOIS.

HOUSEHOLD UTILITY DEVICE.

Application filed October 18, 1926. Serial No. 142,363.

This invention relates to a device which is substantially indispensable, for its utilitarian value, in every household, hence a household utility device.

5 The device consists of the combination of several familiar structures, which have heretofore found separate and single use in and about domestic residences, and which herein are shown combined in a new structure 10 wherein they cooperate to produce new and useful results. The concept necessary to evolve the cooperative usefulness of these familiar household instruments of utility to jointly operate to increase their function and 15 value, is of a high order of the inventive faculty, and new cooperative results are produced by the assembly which is not an aggregation of old devices minus a joint cooperative effect and void of mutual interdependence, but a valuable cooperative association.

One of the objects of the invention is to combine an ironing board with a composite ladder in such manner that their individual functions are not impaired and new cooperative joint results and an extension of their uses are produced by the interdependence of the two elements of the new combination.

Other objects, advantages, benefits and 20 refinements will become apparent from a consideration of the following description and drawings forming a part of this application, wherein

On the drawings:

35 Figure 1 is a perspective elevation of the device as it appears when being used as a step ladder.

Fig. 2 shows the device with the parts folded together in small compass.

40 Fig. 3 shows the device in perspective as when made into a scaffold, to be used for cleaning, painting or papering the walls and ceiling of a room.

Fig. 4 is a side elevation of the device as 45 when used as an ironing board for laundry purposes, and as it is projected from a cabinet in which it may be contained when not in use.

Fig. 5 is a front elevation of a cabinet, with 50 the door open showing the utility device therein.

Fig. 6 is a section taken on line VI—VI of Fig. 1.

55 Fig. 7 is a section taken in line VII—VII of Fig. 5.

Fig. 8 is a section taken on line VIII—VIII of Fig. 1.

In all the views, the same reference characters indicate similar parts.

The device as shown consists generally of 60 an ironing board 10 for laundry purposes hinged at its larger end 11 to a ladder 12. A block or cleat 13 is secured to the end 11 with its longest axis transverse of the board. A pintle shaft 14 extends through the block 65 and projects therebeyond at each end. This shaft serves as a pintle to hinge the board and the ladder together.

In the exemplification shown, the side members 15 and 16 of the ladder are connected together near their lower ends by three steps only, 17, 18 and 19. The space intervening between step 17 and the upper ends of the members 15 and 16 is open, as 70 shown in Fig. 3.

Another shorter ladder 20 has its side members 21 and 22 also hinged on the shaft or pintle 14. This shorter ladder 20, as shown, has three steps 23, 24 and 25, and it is within and parallel with the larger ladder 80 12 and may be extended therefrom about its hinge to form a step ladder as shown in Fig. 3.

The ladder 12 and the ladder 20 are held in positions shown in Fig. 3, to prevent 85 spreading, by a pair of relatively slidable links 27, a pair on each side. The links 27 are secured at each of their ends to the side members of the ladder 12 with the body part spaced away therefrom, and the links 27 90 have each an eye 28 which slides along the guides 26 and another eye or hook 29 pivoted to the front edge of the respective side members 22 and 21. When the ladder 20 is in place within ladder 12, these slidable links 95 change relative positions and are in place as shown in Figs. 1 and 2.

In positions shown in Fig. 3, the lower end of each ladder is in contact with the floor and the board 10 is held in horizontal position by a brace or frame 30, having side members 31 and 32 pivoted to the side members 15 and 16 on the outside thereof at 33. 100

The members 31 and 32 are connected together at their outer ends by a cross member 105 34 and a brace 35.

A cleat 36 extends across the board 10. It carries two laterally projecting metal tongues 37 and 38 which pass through openings 39 and 40 in the cross member 34 to 110

prevent the members 10 and 12 from spreading and relative lateral movement when extended, as shown in Fig. 1.

When the frame or brace 30 is not in use, 5 as in Figs. 1, 3 and 4, it is folded back, as in Fig. 2, with its side members 31 and 32 parallel with the side members 15 and 16 of the ladder 12. A wall cabinet 41 for containing the device when not in use, has side 10 members 42 and 43 and a back wall 44. A door 45 closes the cabinet.

Two blocks 46 and 47 are placed in the lower part of the cabinet and spaced sufficiently to receive the narrower end of the 15 device, as in Fig. 5. The blocks each has a notch opening upwardly to receive the projecting ends 14-14 of the pintle. This forms a hinge upon which the device as a whole may be turned when moved outwardly, by swinging the upper end, as shown 20 in Fig. 4.

In this Figure 4 the board 10 is in horizontal position and may be used as an ironing board.

25 The inner end is supported by the pintle ends 14 resting in the blocks 46 and 47 and the outer end of the board 10 is supported by the composite ladder and the brace 30. By replacing frame 30 in position, parallel with 30 the ladder 12, the latter may be raised on said pivots with the board 10 and the device may be replaced within the cabinet, as shown in Fig. 5 in inverted position.

When the device is taken bodily from the 35 cabinet and extended as shown in Fig. 3, it may be used as a trestle, ironing board or table. When used as a trestle, the shorter step ladder 20 is utilized as means for mounting the structure, which may then be 40 used for supporting a person while cleaning, painting or papering the walls and ceiling of a room.

When the device is used as an ironing board, trestle, table or the like, the board 10 45 is in substantial horizontal position sup-

ported by the ladders 12 and 20, and when it is used as a ladder, the board 10 is placed on end as in Figure 1 and serves as a front support for the ladder structure.

It will be manifest that the ladder structure cooperates with the board in a novel manner to produce certain results, and that the board cooperates with the ladder in a novel manner to produce other results, and that both of them exercise novel functions 55 not usual or possible with either when separated. There is an interdependence of the elements in this new association.

I claim as my invention:

1. In a device of the character described, 60 an elongated board, a pair of ladders foldable into each other and pivotally connected at like ends to an end of said board, a brace frame pivoted to the longer of said ladders and having spaced apertures therein, spaced 65 tongues on the under side of said board engageable in said apertures, and means attached to both of said ladders to limit the pivotal movement therebetween.

2. In a device of the class described, in 70 combination, a board, two ladders pivoted to said board at like ends by a common pivot, said ladders arranged to be separated to support said board in substantially horizontal position; braces pivoted to the longer 75 ladder for upholding the end of the board remote from the pivot, said ladders having sliding co-operating members to limit the spread of the same, said brace and board having interfitting members to prevent relative lateral movement of the same whereby 80 said ladders serve to support said board in horizontal position and said board serves to support said ladder in inclined position, the parts being braced in either position to prevent collapse in use.

In testimony whereof I have hereunto subscribed my name.

HENRY H. HANSEN.
